UNITED STATES PATENT OFFICE.

EDWARD J. STANEK, OF MILWAUKEE, WISCONSIN.

APPARATUS FOR TRUING UP CASTINGS OF VARYING CONTOUR.

Application filed January 4, 1926. Serial No. 79,277.

The invention relates to devices for straightening and truing up castings of varying contour, and more particularly malleable iron castings, such as are used as the differential carrier member on automotive vehicles.

Castings as they come from the molds often vary to a considerable extent from the true dimensions because of the shifting of the cores or the failure to center them properly. Furthermore, where these castings, such as malleable iron castings, are annealed, they sometimes become distorted. In either event such castings cannot be readily chucked for machining to their finished dimensions, and, also, in a differential carrier the walls adjacent the ring gear have to insure the proper clearance for such gear. The object of this invention is to provide an apparatus for straightening or truing up castings, such as malleable iron differential carrier castings, whereby such castings may be held within the tolerances specified by the manufacturer who finishes the castings, and so far as I am aware, until the present invention was devised no satisfactory apparatus existed for truing up differential carriers to bring their dimensions within the close tolerances now demanded by the manufacturer.

The invention further consists in the several features hereinafter set forth and more particularly defined by claims at the conclusion hereof.

In the drawings, Fig. 1 is a vertical sectional view through an apparatus embodying the invention, with the casting being treated shown therein;

Fig. 2 is a view, partly in section, of the apparatus, the section being taken at right angles to that of Fig. 1;

Fig. 3 is a detail sectional view taken on the line 3—3 of Fig. 1, parts being broken away;

Fig. 4 is a sectional view taken on the line 4—4 of Fig. 1;

Fig. 5 is a detail sectional view taken on the line 5—5 of Fig. 1, the casting being omitted;

Fig. 6 is a vertical sectional view of a differential carrier taken on the line 6—6 of Fig. 8;

Fig. 7 is a similar sectional view taken on the line 7—7 of Fig. 8;

Fig. 8 is a plan view of the differential carrier shown in Figs. 1, 2, 6 and 7;

Fig. 9 is a vertical sectional view of an

apparatus embodying the invention, with certain additional features over that shown in Fig. 1, and with a differential carrier having certain modifications;

Fig. 10 is a view similar to Fig. 9 and taken at right angles thereto;

Fig. 11 is a plan view of the differential carrier shown in Figs. 9 and 10;

Fig. 12 is a sectional view taken on the line 12—12 of Fig. 11;

Fig. 13 is a section taken on the line 13—13 of Fig. 11.

Figs. 6 to 8, inclusive, show a differential carrier C, of known form, wherein the numeral 14 designates the tubular end portion designed to receive the propeller shaft of an automotive vehicle, 15 the flanged end designed for connection with the differential housing, 16 the ring gear cavity, and 17 the bearing lugs for the rear axle shafts of the vehicle. In carriers of this form or general type the tubular end 14 is subjected to certain machining operations and the inner wall forming the ring gear cavity 16 must have enough clearance to accommodate the ring gear that rotates therein. Carriers of this kind are generally made of malleable iron castings which are annealed after casting, and due to the fact that during the casting process and the subsequent annealing process certain inaccuracies frequently occur. Such castings have to be trued up so that the subsequent machining and assembling may be readily and accurately accomplished, and the apparatus shown in Figs. 1 to 5, inclusive, is used for this purpose.

This apparatus includes a relatively fixed die member 18 having another die section 19 associated therewith and adjustable relative thereto by means of shims 20 and a die member 21 cooperating with the members 18 and 19 and associated with a ring section 22, the members 21 and 22 being held together and to a head member 23 by a centrally disposed bolt 24, said head member adapted to be engaged by the pressing plunger or platen of any suitable press to accomplish the truing up operation. The members 21 and 22 may be spaced at different distances from the head member 23 by means of shims 25 and 25' of the desired thickness.

With this construction oppositely disposed sides 26 of the member 18 and similar sides 27 of the die section 19 are curved to take the outer curved side 28 of the casting, and the die member 21 is similarly curved to en-

gage the inner side 29 of the wall forming the ring gear cavity 16 so that when pressure is put upon the member 18 by the action of the press upon the head member 23, this curved wall of the casting forming said cavity 16 will be pressed or squeezed into the desired true form to insure proper assembly of the ring gear in said cavity. At the same time the flange 30 at the upper end of the casting will be pressed flat between the top 31 of the die section 19 and the ring section 22.

In addition to truing up the inner wall of the cavity 16 and the flange 30, semicylindrical die blocks 32 are secured between the die member 21 and the head member 23 at their inner ends and project outwardly therefrom to engage in the semicylindrical bearing recesses 33 in the lugs 17 of the castings to true these recesses up during the pressing operation above referred to. Thus portions at one end of the carrier are pressed into the desired true shape, and means are also provided for simultaneously truing up the tubular end 14 of the casting.

This last-named means includes a casing and die guide member 34 which is mounted in an annular recess 35 in the lower end of the member 18 and may be adjustably spaced therefrom at its upper end by a ring or washer 36, to accommodate castings of different lengths, and at its lower end rests upon another ring member 36' which in turn engages a base plate 37 seated in the base portion of the member 18.

Associated with the member 34 are a plurality of straightening die sections 38, a stripper-plate 39, springs 40 associated with said plate, and springs 41 associated with said dies 38.

The casing or die guide member 34 has a wedge-shaped surface or surfaces, and in the case of a tubular casting, as here shown, the surface 42 is of conical form extending to a cylindrical surface 43 in which the stripper-plate 39 is disposed. The straightening dies 38 are of complementary form to form a contractible die, each having a wedge-shaped outer surface 44, and are in the form of segments of a conical surface to cooperate with the conical surface 42, and are normally separated by the springs 41 seating in bores 45 in the adjacent dies. The inner wall 46 of each of the dies 38 is shaped to conform to the trued up shape of the article to be straightened, and in the present instance these walls form segments of a cylindrical surface to receive the tubular end of the casting. Adjacent the wall 46 each die section 38 has an inwardly extending stop portion 47, here shown as a flange, the flanges of adjacent sections being designed to form an inwardly extending ledge against which the end 48 of the tubular portion 14 of the casting abuts. The die sections adjacent

the wall 46 may be relieved above this part by tapering wall portions 49 to permit ready insertion of the tubular end of the casting within the cavity formed by the dies.

Ring members 36' of varying thickness 70 may be interposed between the member 34 and the base plate 37 so that said member 34 in which the dies 38 are mounted may be raised or lowered to adjust the dies for different lengths of travel relative to the member 34 and hence accommodate castings of varying external diameters. 75

With this construction, before and during the time the upper part of the casting is being pressed to the desired true form, the press, through engagement with the head member 23 and the die member 18, causes the tubular end 14 of the casting to move downwardly into the cylindrical cavity formed by the dies 38. During this downward movement the end 48 of said casting engages the stop portions 47 of the dies 38 and hence during this movement these dies are moved with the casting relative to the guide member 34 which by reason of the 80 tapered contact between said member 34 and said dies 38 causes said dies to be moved inwardly and contract about the lower end, and at the time the upper parts of the casting have been straightened and have reached 85 a stop position the dies 38 have pressed or squeezed the outer surface of the tubular end 14 of the casting of the desired size and hence this end has been trued up so that it may be readily chucked for subsequent 90 machining operations. Thereafter the release of pressure upon the upper part of the casting allows the springs 40 to act on the plate 39 and push the dies 38 upwardly and loosen them from wedging engagement with the member 34, and as soon as said sections are free they are pushed apart by the springs 41 acting upon them and thus the lower end of the casting is freed from the die and as the upper movable dies have been moved upwardly by the press the casting may be removed from the apparatus. 100

In the differential carrier shown in Figs. 11 to 13, inclusive, there are certain modifications over that previously described and there are certain additions for the apparatus used in connection with this carrier. As shown, this carrier has a short tubular end portion 50 designed to receive the propeller shaft, a laterally extending shaft-bearing 115 portion 51, a ring gear cavity 52, the attaching flange 53 and the rear axle shaft-bearing lugs 54.

The lower tubular end 50 is straightened by the dies 38', similar to the dies 38 and 120 having stop flanges 47' similarly associated with said end and similarly associated with the conical die guide member 55, the base-plate 56, springs 57, stripper-plate 58, springs 59, spacing rings 60 and 61, these 125

parts being respectively similar to the parts 34, 37, 40, 39, 41, 36 and 36' of the first-described construction, and operating in a similar manner to squeeze or form the outer 5 wall of the tubular end 50 to the desired external dimensions, it being noted that one of the dies 38' has a recess 62 formed therein to accommodate the lugs 63 on said carrier.

The inner curved wall of the cavity 52 and 10 the flange 53 are trued up by parts 18', 19', 20', 21', 22', 23' and 24', similar to the parts 18 to 24, inclusive, previously described, and laterally extending semicylindrical blocks 64, generally similar to the blocks 32 engage 15 the recesses 65 in the lugs 54. In addition, flat-faced blocks 66 suitably secured to the ring section 22' engage the outer side 67 of the lugs 54 to true these sides up. These 20 parts act upon the casting similarly to corresponding parts of the first-described construction to true up the cavity 52, the flange 53 and the lugs 54, as the lower tubular end 50 is pressed to the desired size and form.

In addition, the upper composite movable 25 die is provided with a disk 68 engageable with the apertured boss 69 of the portion 51 during the downward movement of said upper die and cooperates with a cylindrical anvil die 70 secured to the base plate 56 to 30 straighten this portion 51 as the other parts of said casting are trued up.

Thus, by a simple pressing operation all 35 the parts of the carrier whose dimensions must be kept within certain limits are brought to these limits so that subsequent machining and assembling operations may be readily accomplished.

I desire it to be understood that this invention is not to be limited to any particular form or arrangement of parts except in 40 so far as such limitations are specified in the claims or necessitated by the prior art.

What I claim as my invention is:

1. In an apparatus for truing up differential carrier castings, each having a ring gear cavity portion and a tubular end portion, the combination with cooperative relatively movable dies for truing up the ring gear cavity portion of said casting, of means for simultaneously truing up the tubular end portion 45 of said casting including a plurality of dies engageable with said end portion and movable therewith during the straightening operation.

2. In an apparatus for truing up differential carrier castings, each having a ring gear cavity portion, a flange, bearing recesses and a tubular end portion, the combination with cooperative dies for truing up the ring gear cavity portion, the flange and the bearing 55 recesses of said casting, of means for simultaneously truing up the tubular end portion of said casting.

3. In an apparatus for truing up differential carrier castings, each having a ring gear cavity portion, a flange, bearing lugs, bearing recesses and a tubular end portion, the combination with cooperative dies for truing 60 up the ring gear cavity portion, the flange, and the bearing lugs and the bearing recesses 65 of said casting, of means for simultaneously truing up the tubular end portion of said casting.

4. In an apparatus for truing up differential carrier castings, each having a differential housing end and a tubular end, the combination with relatively movable cooperative dies acting upon the differential housing end of said carrier to straighten said end, of a plurality of straightening dies acting upon the tubular end of the carrier and actuated by the movement of said carrier on its movement by the movable die of the first-named cooperative dies.

5. In an apparatus for truing up differential carrier castings, each having a laterally extending shaft-bearing portion, a ring gear cavity, a flange, bearing lugs and a tubular end portion, the combination of cooperative dies for truing up the ring gear cavity, the flange, the bearing lugs and said shaft-bearing portion of said casting, and contractible dies for truing up the tubular end portion 90 of said carrier simultaneously with the truing up operation of said cooperative dies.

6. In an apparatus for truing up differential carrier castings, each having a laterally extending shaft-bearing portion, a ring gear cavity, a flange, bearing lugs and a tubular end portion, the combination of cooperative dies for truing up the ring gear cavity, the flange, the bearing lugs and the shaft-bearing portion of said castings, and means for simultaneously truing up the tubular end portion of said casting.

In testimony whereof, I affix my signature.

EDWARD J. STANEK.
